UNITED STATES PATENT OFFICE.

LEWIS C. MYERS, OF FREEPORT, NEW YORK, ASSIGNOR TO ROYAL TYPEWRITER COMPANY, INC., OF NEW YORK, N. Y., A CORPORATION OF NEW YORK.

TYPEWRITING MACHINE.

Application filed October 18, 1927. Serial No. 226,953.

This invention relates to a type action for typewriting machines in which there are a plurality of sliding type bars which converge to a common printing center and each 5 type bar is provided with a plurality of groups of two type each. Each type bar is operated by two key levers for the purpose of selecting the desired type of each group and the platen is shifted in the usual or any 10 desired manner in order to bring it into a position to cooperate with the selected group of types.

The sliding type bars are actuated by a toggle mechanism which reaches a straight 15 line position at the time of printing so that the actual printing is performed by pressure rather than by impact. Means are provided for obtaining a relative adjustment between the normal position of the platen and the 20 type bars in order that the force of the imprint may be varied as may be desired for manifolding.

One of each pair of keys merely gives the 25 type bar its sliding movement, while the other key not only gives the type bar the same sliding movement, but gives a lifting movement to a guide member which supports the type bar in its travel to the printing point, thereby lifting the bar into position 30 so that another type of the group is brought to the printing point. The type bar is given its sliding and lifting movements at substantially the same time but the lifting movement is completed before the type bar reaches 35 the printing point and the connections between the second key lever and the guide which lifts the type bar are such that the key lever may be moved a slight further distance after the guide has reached the full extent of its movement.

The connections between the key lever and the toggle member in the present embodiment of the invention comprise two bell crank levers with the necessary link connections 45 and are so arranged that the type bar moves the greater part of the distance to the printing point during a relatively small part of the movement of the key levers so that each type bar recedes from the printing position very rapidly upon the release of the key lever. The intermediate connections are also so arranged that only a very light touch is necessary to produce the printing movement of the 50 type bar.

Other objects of the invention will be apparent from the following detailed description and will be set forth in the appended claims.

In the drawings:

Figure 1 is a side elevation of a single type 55 action with parts in fore and aft section, the full line position denoting the normal position of the parts and the dotted line position denoting the printing position when one of the key levers is depressed.

Figure 2 is a similar view showing in full 60 lines the position taken by the parts when the other of the key levers which control the same type bar is fully depressed.

The invention may be embodied in type- 65 writing machines of widely different character in other respects, and for this reason the other instrumentalities of the typewriting machine have not been illustrated. There is indicated in platen A which is movable to 70 a second position indicated in dotted lines by any usual or desired form of case shift mechanism.

Each type bar 1 is mounted to slide and is 75 preferably made in skeleton form for the sake of lightness and is provided with four type a, b, c, and d. When the platen is in its lower position as shown in Figure 1, operation of the type bar will print from one of the type c or d. If the type bar is given 80 merely its longitudinal movement, the printing impress will be from the type c as indicated in Figure 1 while if the type bar is simultaneously lifted by the depression of the other key which operates the same, the 85 imprint will be from the type d as shown in Figure 2. If it is desired to print from types a or b, the platen is shifted to the dotted line position and the two key levers control 90 the selection of the types a or b in similar 95 manner.

Each type bar is guided on a supporting 100 frame member 2 which forms one part of a bell crank lever and is pivoted at 3 to a support carried by the machine frame. This member 2 has upward projections 4 which bear against the sides of the type bar and serve to guide it in its sliding movement. Riveted or otherwise fastened to the member 2 at 5 is a plate 6 which extends upwardly and 105 has bent over ears 7 engaging the upper edge of the type bar. The projections 4, plate 6 and ears 7 which engage the type bar at

different points along its length serve to guide the same accurately to the printing point.

Attached to an intermediate portion 8 of 5 the type bar at 9 is a link 10. This link is illustrated as two parallel members connected by web portions 11 and 12. This is primarily for convenience in manufacture and to add stability to the parts, but it is 10 possible to omit the web portions 11 and 12 and employ merely two parallel link members or if desired a single link member may be used. It is, however, preferable to employ the double members since one of these 15 passes on each side of the type bar and serves to guide the rear end thereof in its movement. Pivoted at 13 to the link 10 is a short link 14 which together with the link 10 forms a toggle member. This link 14 is pivoted at 20 its other end at 15 to a supporting member 16 mounted in the frame of the machine. An extension 17 from the member 16 passes through a bar 18 carried by the frame of the machine and is held in adjusted position by 25 a set screw 18'. A screw threaded into the member 18 has a head 19 which fits in a cut-out 20 of the extension 17 so that the movement of the screw will adjust the position of the member 16. This member 16 not only 30 supports the link 14 but as will be noted, supports the remainder of the intermediate connections between the key lever and the link 14. An adjustment of the member 16 will, therefore, determine the effective printing 35 position of the type bar and by adjusting the intermediate connections will preserve the desired relation between the various parts. It may be noted that it is also possible to mount the members 16 rigidly and 40 obtain the desired adjustment between the platen and type bar by adjusting the platen in any well known or desired manner.

Pivoted at 21 to an ear intermediate the 45 ends of the link 14 is a link 22 pivoted at its other end at 23 to one arm 24 of a bell crank lever which is pivotally supported at 25 on the member 16. The arm 24 is provided with an ear 26 to which is attached one end of a spring 27, the other end of 50 which is fast to a portion of the member 16. This spring 27 assists in breaking the toggle and returning the parts to normal position when pressure is removed from the key lever. The lower arm 28 of this bell crank lever is 55 connected by a link 29 to an arm 30 which is pivoted at 31 to the lower end of the member 16.

Key levers 32 and 33 are pivoted at 34 and 60 are returned to normal position by springs 35 which are connected to a bridge member 36 carried by the machine frame. The key lever 32 is connected by a link 37 to one arm 38 of a bell crank pivoted on the axis 31 and having its second arm 39 provided with

a bent over ear 40 which overlies the arm 30. 65 The other key lever 33 of each pair is connected by a similar link 37' to one arm of a bell crank 41 also pivoted on the axis 31 but lying on the other side of the link 30 and being slightly longer than the corresponding arm 39 of the other bell crank lever. This bell crank lever 41 is provided with an offset ear 42 which also overlies the arm 30. It is evident from this construction that a depression of either of the key 70 levers will operate the arm 30 and the whole type action without affecting the position of the other key lever of the pair.

The supporting and guiding member 2 has a downwardly extending arm 43 which is 75 connected by a lost motion pin and slot connection 44 to a bell crank lever 45 which is pivoted at 46 to the upper end of a lever 47 which is in turn pivoted at 48. The bell crank lever 45 has an arm 49 and the lever 47 80 has a projection 51 which is connected to the arm 49 by a spring 50. It is obvious that this construction will cause the lever 47 and the bell crank 45 to move normally 85 together but will permit an additional movement of the lever 47 after the bell crank 45 and the guiding member 2 have been moved to the limit of their movement. This additional movement will, of course, tension the 90 spring 50. The lever 47 is limited in its 95 movements by adjustable stop screws 52 and 53 carried by a plate 54 attached to the bell crank 45.

The supporting and guiding member 2 has a lug 55 on the lower side thereof which normally engages an adjustable stop screw 56 threaded into a frame member 57. The engagement of this lug with the stop screw determines the normal position of the parts as shown in Figure 1. When the member 2 is 100 lifted by the depression of the second key lever of each group, the lug 55 will engage the underside of the head 58 of an adjustable stop screw 59 threaded into the frame member 57. This will limit the upward movement of the guiding member 2 and the type 105 bar 1 and the position of the parts will be that shown in Figure 2. The guiding member 2 is normally held in its lower position by a spring 60 connected thereto at one end and 110 at its other end to a fixed part 61.

The movement of the bell crank lever and 115 lever 47 which results in lifting the type bar is brought about by the engagement of a pin 62 on the lever 33 which in its downward 120 movement engages a cam 63 on the lower end of the lever 47 thereby rocking the same from the Figure 1 to the Figure 2 position. This cam has a slight dwell portion so that the parts are held in substantially fixed position 125 at the lower portion of the movement of the key lever.

There may also be provided an additional

guiding means 64 for the lifting member 2 which is shown as an integral portion of the frame 57.

The supporting and guiding member 2 is normally inclined slightly below the horizontal and when lifted to bring the type *d* into printing position, it moves to an equal distance above the horizontal. This results in the same action in both positions of the type bar. It is also noted that by the provision of separate adjustments for each supporting member 16, the printing position of each type bar may be varied individually. If the platen is adjusted for this purpose, it is of course impossible to obtain this desired result.

From the foregoing it will be apparent that when the platen is in lower case position and it is desired to print the type *c*, the key lever 32 will be depressed. The depression of this key lever does not tilt the supporting frame because there are no connections between said lever and said frame. The lever, however, through the medium of the link 37, bell-crank lever 38, arm 30, link 29, bell-crank lever 24, 28, and link 22, operates the toggle 10, 14 and thereby moves the type bar rearwardly to print the type *c*.

When the platen is in lower case position and it is desired to print the type *d*, the key lever 33 will be depressed. This lever, through the medium of the link 37', bell-crank lever 41, arm 30, link 29, bell-crank lever 24, 28, and link 22, operates the toggle 10, 14 and thereby moves the type bar rearwardly to print the type *d*.

The depression of this lever will tilt the frame 2 and thereby elevate the rear end thereof. This action is effected by the pin 62 engaging the cam 63 on the depending arm of the lever 47, rocking said arm on its pivot 48 to cause the lever 45 to swing and thereby tilt the frame 2. Then, while the pin 62 is engaged with the dwell portion of the cam 63, the frame 2 is retained in its inclined position during the last part of the depression movement of the key lever 33 and during the last part of the printing movement of the type bar.

When it is desired to print either of the types *a* or *b*, the platen is first elevated to upper case position. Then if the type *a* is to be printed, the key lever 32 will be depressed and the mechanism will operate in the same manner as described in connection with the type *c*, whereas if the type *b* is to be printed, the key lever 33 will be depressed and the mechanism will operate in the same manner as described in connection with the type *d*.

Thus, there is provided a vertically movable support on which the type bar slides, connections between the type bar and both key levers which are operative upon the depression of either key lever to slide the type bar to printing position, and other connec-

tions between the support and one of the key levers only which are operative upon the depression of the last mentioned key lever to vertically move the support.

While the type action is illustrated in a construction in which the key levers are depressed throughout their full extent manually, nevertheless the action may be embodied in a power operated machine if desired. It is apparent that the detail construction may be widely varied without in any way departing from the spirit of the invention, and the drawings are, therefore, to be regarded as illustrating and not as limiting the invention in any way.

I claim as my invention:

1. A type action comprising a slidable type bar provided with a plurality of groups of type, the types being arranged vertically one above the other, key levers associated with the type bar and corresponding in number to the number of type in each group, a pivoted support upon which the type bar slides, connections between the type bar and the key levers operative upon the depression of each key lever for sliding the type bar to printing position, said connections including a pivoted operating arm, and separate connections between the operating arm and the respective key levers, and other connections between the support and one key lever only and operative upon the depression of said key lever for tilting said support to bring another type to printing position.

2. A type action comprising a slidable type bar provided with a plurality of groups of type, the types being arranged vertically one above the other, key levers associated with the type bar and corresponding in number to the number of type in each group, a pivoted support upon which the type bar slides, connections between the type bar and the key levers operative upon the depression of each key lever for sliding the type bar to printing position, and other connections between the support and one key lever only and operative upon the depression of said key lever for tilting said support to bring another type to printing position, said support in normal position being inclined downwardly from the horizontal in one direction and in shifted position being inclined upwardly an equal distance from the horizontal in the other direction.

3. A type action comprising a slidable type bar provided with two groups of type, two key levers associated with the type bar, and means for operating the type bar from either key lever, said operating means including a pivoted arm connected to the type bar, two bell-crank levers independently engageable with the pivoted arm, and links respectively connecting the bell-crank levers and the key levers whereby the depression of either key lever will move the type bar to printing position.

4. A type action comprising a slidable type bar provided with two groups of type, the types being arranged vertically one above the other, two key levers associated with the type bar, a vertically movable support upon which the type bar slides, means for moving the type bar to printing position upon the depression of either key lever, and means controlled by the depression of one key lever 5 only for vertically moving said support, said controlling means including an arm fixed to the support, a bell-crank lever fulcrumed on a fixed axis, a lever pivoted on the bell-crank lever for limited movements relative thereto 10 and having pivotal connection with said arm, and a pin and cam connection between the bell-crank lever and said key lever.
5. A type action comprising a slidable type bar provided with two groups of type, the types being arranged vertically one above the other, two key levers associated with the type bar, a vertically movable support upon which the type bar slides, means for operating the type bar from either key lever including a 15 pivoted arm connected to the type bar, two bell-crank levers independently engageable with the pivoted arm, and links respectively connecting the bell-crank levers and the key levers whereby the depression of either key 20 lever will move the type bar to printing position, and means controlled by the depression of one key lever only for vertically moving said support.
6. A type action comprising a slidable type bar provided with a plurality of groups of type, key levers associated with the type bar and corresponding in number to the number 25 of type in each group, a movable support for the type bar, means for operating the type bar which includes a plurality of bell crank

levers pivoted to a fixed support, means whereby the operation of each of said bell crank levers will operate the type bar, and means connected to one bell crank lever for shifting the movable support.

7. A type action comprising a slidable type bar provided with a plurality of groups of type, key levers operatively associated with the type bar and corresponding in number to the number of type in each group, and means for operating the type bar from either key lever including an operating arm mounted on a fixed pivot, and separate connections between the operating arm and the respective key levers.

8. A type action comprising a slidable type bar provided with two groups of type, the types being arranged vertically one above the other, two key levers associated with the type bar, a vertically movable support upon which the type bar slides, means for moving the type bar to printing position upon the depression of either key lever, and means controlled by the depression of one key lever only for vertically moving said support, said controlling means including an arm fixed to the support, a bell-crank lever fulcrumed on a fixed axis, a lever pivoted on the bell-crank lever for limited movements relative thereto and having pivotal connection with said arm, stops 60 carried by one of the levers for cooperation with the other lever to limit relative movements of said levers, a spring connecting said levers for yieldably retaining one lever against one of the stops, and a pin and cam connection between the bell-crank lever and said key lever.

In testimony whereof, I have hereunto subscribed my name.

LEWIS C. MYERS.
